BENDER TYPE ELECTROMECHANICAL DEVICE WITH DIELECTRIC OPERATING ELEMENT

Hans Jaffe, Cleveland Heights, Ohio, assignor to
The Brush Development Company, Cleveland,
Ohio, a corporation of Ohio

Application April 9, 1947, Serial No. 740,461

6 Claims. (Cl. 171—327)

1

This invention relates to electromechanical transducers of the general type known as "benders," in which mechanical action results from the application of an electric field and vice versa. More particularly, it relates to improved bender type electromechanical devices which are highly stable with reference to temperature and humidity conditions.

Electromechanical transducers of the piezoelectric type are well known in the art. One such arrangement has comprised Rochelle salt as the operating element thereof and transducers of this type are widely used commercially. However, the properties of Rochelle salt are such that transducers comprising this material as an operating element do not provide entirely satisfactory operation under some operating conditions. For example, the temperature of such a unit must be maintained at all times below a rather low maximum value or otherwise the piezoelectric properties of the operating element are destroyed. Also, it is well known that such operating elements are somewhat fragile and, inasmuch as Rochelle salt is hygroscopic, it is necessary in transducers of the type under consideration to insure that the operating properties of the unit are not adversely affected by humidity conditions.

Electromechanical transducers of the "bender" type are also well known in the art, being described, for example, in U. S. Letters Patent Re. 20,213, granted to C. B. Sawyer on December 22, 1936. Such bender elements, as heretofore used, have generally comprised an operating element consisting of two layers of some piezoelectric material.

In the research work leading to the present invention, it was discovered that certain ceramic materials, having some very desirable operating characteristics, could be utilized to provide an operating element generally analogous to that of a piezoelectric operating element. One such arrangement is described in full in my copending application, Serial No. 740,460, filed concurrently with the present invention and assigned to the same assignee as the present invention. This copending application discloses an arrangement using a ceramic dielectric material which is polarized to provide an action somewhat of the nature of that provided by the crystal which is frequently used in crystal transducers. The specific

2

arrangement disclosed in the copending application for polarizing the material of the operating element comprises the application of a high unidirectional electrical field thereto. It would be desirable to provide a "bender" type of operating element for an electromechanical transducer which uses dielectric material as the operating element, and it is to this that the present invention is directed.

10 It is an object of the present invention to provide an improved electromechanical transducer of the type in which mechanical action results from the application of an electrostatic field, and vice versa.

15 It is a further object of the invention to provide an improved electromechanical transducer which may be readily and inexpensively produced and which is rugged and relatively immune to the influences of extraneous conditions such as temperature and humidity effects.

20 In accordance with the invention there is provided a bender-type electromechanical device comprising an even number of superimposed layers of dielectric material. These layers comprise

25 two groups of elements, one of which is to expand while the other group is to contract, and vice versa, to provide a bender type of electromechanical transducer element. There is also provided unidirectional electrical polarizing means for each

30 of the layers. Also electrical terminal connections are provided for each of the layers, such that the charges which would be associated with the application of a voltage thereto are of the same sign in each of the layers of one of the two above-mentioned groups of elements as the charge in each layer of the group due to the polarizing means, while the charges in each of the layers of the other of the two above-mentioned groups due to the applied voltage are of the opposite sign to the charge in each layer of the last-mentioned group due to the polarizing means. By this arrangement the device can be used to convert bending movements of the transducer element into electrical energy, or vice versa.

45 For a better understanding of the present invention together with other and further objects thereof, reference is had to the following description taken in connection with the accompanying drawings, and its scope will be pointed out in the appended claims.

50

Referring now to the drawings, Figure 1 is a broken-away isometric view of a phonograph pickup embodying a bender-type electromechanical device in accordance with the invention; Figures 2, 3 and 4 illustrate various circuit connections suitable for use with the transducer element of Figure 1; Figures 5 and 6, respectively, illustrate alternate embodiments of the invention utilizing a larger number of layers of material in the actuating element; while Figure 7 illustrates a bender type actuating element for an electro-mechanical transducer device utilizing layers of material of circular shape.

Referring now to Figure 1, there is illustrated a bender type electromechanical device in accordance with the invention embodied in a phonograph pickup of well known design. In this phonograph pickup, a needle chuck 10 is mounted on elastic bearings 11, 12 in a two-part molded housing, only one part 13 of which is shown for the sake of simplicity. Enclosed within the housing is an operating element comprising two plates or layers of dielectric material 14, 15 cemented together face-to-face, with an electrode 16 between them and electrodes 17 and 18 on the outer faces. The material of which the elements 14 and 15 are comprised is one which normally does not have the property of a substantially linear relationship as a first order effect between its electrical and mechanical actions but which can be, as described in full in the above-mentioned copending application, polarized by the application of a unidirectional electrical field to respond to the fundamental component of an alternating electrical field applied thereto in at least one mechanical mode. The operating element comprising the layers 14 and 15 of dielectric material is mounted within the housing between similar soft pads 19, 20 of rubber or like material engaging it at one end. The element is engaged at its other end by a fork-like extension 22 of the needle chuck 10. A thin sheet of rubber or like material 23 is disposed between the operating element and the needle chuck to act as a compliant coupling member and to provide insulation to prevent short-circuiting of the electrodes 17, 18 by the needle chuck. The three electrodes are connected to pin-like terminals 25, 26 and 27.

Neglecting for the moment the polarizing action, which is mentioned above, when lateral vibrations are applied to the needle 28, vibratory bending forces are applied by the chuck to the two-plate crystal assembly, setting up alternating compression and tension forces. Thus when the needle is moved in the direction indicated by the arrow A, the plate or layer 14 is subjected to compression forces and the plate or layer 15 is subjected to tension forces. Conversely, when the needle is deflected in direction B, plate 15 is subjected to compression forces, and plate 14 is subjected to tension forces. When, as will be subsequently described, the plates are suitably polarized, alternating potential differences are developed at the terminals 25, 26, 27 in response to the vibrations of the needle. Suitable circuit connections for the arrangements of Figure 1 are illustrated in Figures 2, 3 and 4, in which circuit elements which correspond to those of Figure 1 have identical reference numerals.

Referring now to Figure 2, an arrangement is shown in which the operating element supplies input signals for a vacuum-tube amplifier 30. The center electrode 16 of the operating element is connected through a condenser 56 to the input electrode of tube 30, the outer electrode 18 of the

operating element being grounded. The other outer electrode 17 is connected to a unidirectional source 31 which is used to polarize the operating elements of the transducer of the invention. The negative terminal of the source 31 is grounded. If the alternating impedance of the source 31 is high, a by-pass condenser 32 may be shunted across it. A grid leak resistor 33 is provided for tube 30.

Coming now to a consideration of the operation of the arrangement of Figure 2, it will be seen that, with the circuit connection shown, the two plates or layers 14 and 15 are connected in series with the battery 31. Under these conditions, the charges resulting from the connection of the battery are illustrated by the plus and minus signs to the left of the operating element. For alternating currents, however, the two plates are connected in parallel with the input electrodes of tube 30 since the electrode 17 is effectively connected to the electrode 18 through the potential source 31 or through the by-pass condenser 32. When the plates are polarized as shown, if a potential were applied to the alternating current output terminal it would tend to develop charges in one of the plates which correspond in sign to the component of charge developed in the same plate by the unidirectional polarizing source 31, while charges of reverse sign are simultaneously developed in the other plate. This relationship is illustrated by the plus and minus signs to the right in the operating element. Under these conditions, the induced charges due to a bending force are of the same sign as applied to the input circuit of the vacuum tube 30.

It will be seen, therefore, that the arrangement described comprises an even number (specifically two) of superimposed layers of dielectric material comprising two groups of elements, one group of which is to expand while the other group of which is to contract, and vice versa, to provide a bender type of electromechanical transducer element. In the case under consideration there is only one layer (specifically layer 14 or 15) in each of the two groups of elements mentioned. Also, it will be seen that the source 31 comprises a unidirectional electrical polarizing means for each of the layers mentioned. Furthermore, electrical terminal-circuit connections are provided for each of the layers such that the charges associated with a theoretical application of voltage thereto, are of the same sign in each of the layers of one of the two groups of elements as the charge in each such layer of the one group due to the polarizing means. Also, it will be seen that the charges in each of the layers of the other of the two groups of elements due to this theoretical application of voltage are of opposite sign from the charge in each such layer due to the polarizing means. It is therefore seen that the device is used to convert bending movements of the transducer element into electrical energy for application to the input circuit of tube 30.

In Figure 3 is illustrated an arrangement in which the two plates are polarized in parallel while being connected in series for alternating signals as applied to the input circuit of the tube 30. In Figure 3 the outer electrode 17 is connected directly to the grid of tube 30 while the outer electrode 18 is connected to ground. A unidirectional path between the outer electrode 17 and ground is provided by the grid leak resistor 33. The polarizing source 31 is connected between ground and the inner electrode 16 through a high resistance 35 and a switch 36. The plus

and minus signs shown to the left in the figure illustrate the components of charge due to the battery action. It will be noted that in this case the polarity of the upper plate is reversed with reference to the polarity shown in Figure 2. However, for signal potentials the upper plate is also reversed as shown by the plus and minus signs to the right so that the voltages developed by a bending of the element are additive in the input circuit of vacuum tube 30. Here again it will be seen that the charges associated with theoretical application of voltage to the plates 17, 18 are of the same sign in the top layer as the charge due to the action of the polarizing means, while the charge associated with the theoretical voltage in the bottom layer is of opposite sign from the charge associated with the battery.

Still another way of utilizing the element of Fig. 1 is illustrated in Fig. 4. In this case the outer electrode 17 is connected to the grid of a tube 38, and the outer electrode 18 is connected to the grid of a tube 39. The two tubes have their output circuits connected together through a push-pull transformer 40. Unidirectional paths from the grids and outer electrodes to ground are provided by grid-leak resistors 41, 42. The two outer electrodes are thus held at the same average unidirectional potential. The inner electrode 16 is connected through switch 36 to the polarizing source 31. In this case the plates are polarized in parallel but are effectively in series for signal voltages as in Fig. 3.

In Fig. 5 there is illustrated a bender element comprising four layers or plates 42, 43, 44 and 45. In order to provide a bender element with four plates, it is necessary for the plates 42 and 43 to expand when the plates 44 and 45 contract, and vice versa. In order to provide this effect so that the unit can be operated either to convert a bending motion into an electrical output signal or an electrical input signal to a bending motion of the element, it is necessary to provide proper circuit connections. The principle which is to be followed in this case, also, is that the component of charge due to polarizing, of two layers on one side of the center axis, should be of the same sign as the component of charge due to the theoretical application of a voltage to the A. C. terminals of the unit while the charges in the other two plates should be of opposite sign from those due to the theoretical application of voltage. In order to effect this result, the circuit connections of Fig. 5 are provided. Thus the positive terminal of the polarizing source 31 is connected by conductor 47 to the electrode between plates 44 and 45 while the negative terminal of the source 31 is connected by a conductor 48 to the electrode between plates 42 and 43. The outside electrodes of plates 42 and 45 are connected together by a conductor 49. The alternating-signal terminals 50 and 51 of the unit are illustrated and terminal 50 is directly connected to the conductive element between the plates 43 and 44 and to the outside electrodes. Terminal 51 is connected to the electrode between plates 42 and 43 directly and, through an isolating condenser 52, to the conductive electrode between plates 44 and 45.

In considering the operation of the arrangement of Figure 5 it will be seen that the components of charge in the plates 42 and 45 due to the polarizing source 31 are as indicated by the polarity signs to the left. Also, the components of charge due to an applied signal voltage or to an induced signal voltage in the case of a bending of the element may be as illustrated

by the plus and minus signs on the right. Here again it is seen that the components of the two charges under consideration are of the same sign in plates 42 and 43 and are of opposite sign in plates 44 and 45. As stated above, this is the requirement for bender type of element in accordance with the invention. It will be seen, therefore, that the arrangement of Figure 5 comprises an even number (specifically four) of superimposed layers of dielectric material comprising two groups of elements (specifically group 42, 43 and group 44, 45) one group of which is to expand while the other group is to contract, and vice versa, to provide a bender type of electromechanical transducer element. The terminal-circuit connections are such that the charges associated with an application of voltage to the A. C. signal terminals of the transducer elements are of the same sign in each of the layers 42, 43 of one of the two groups as the charge in each said layer 42 or 43 due to the polarizing means 31, while the charges in each of the layers 44, 45 of the other of the two groups of elements due to this application of voltage are of opposite sign from the charge in each such layer 44 or 45 due to the charge therein resulting from the polarizing means. This relationship is clearly shown by the polarity signs of the figure.

A different circuit arrangement is illustrated in Figure 6 where circuit elements which correspond to those of Figure 5 have identical reference numerals. In this case, the positive terminal of the polarizing source 31 is connected directly to the electrode common to plates 44 and 45 and to the electrode common to plates 42 and 43 through a resistor 54. The negative terminal of source 31 is connected to the outer electrode of plate 42, the electrode common to plates 43 and 44, and the outer electrode of plate 45 through resistors 55, 56 and 57 respectively. The resistors 54 to 57, inclusive, are isolating resistors for alternating currents. Terminal 50 in this case is connected directly to the electrode common to plates 42 and 43 and to the outer electrode of plate 45 while terminal 51 is connected directly to the outer electrode of plate 42 and to the electrode common to plates 44 and 45.

In view of the description of the operation of the Figure 5 embodiment of the invention which has been given above, it is deemed entirely unnecessary to give a detailed description of the operation in Figure 6. It is sufficient to say that the arrangement is such that, upon application of an alternating voltage to terminals 50, 51, corresponding bending movements of the operating element including plates 42 to 45 are provided. Conversely, a vibratory bending movement of the operating element comprising plates 42 to 45 results in the generation of an alternating voltage which is available at terminals 50, 51. The arrangement of Figure 5 or the arrangement of Figure 6 may be used, for example, in a pickup device similar to that of Figure 1.

The arrangement of Figure 7 is generally similar to that of Figure 2 and corresponding elements have identical reference numerals while similar elements have identical reference numerals primed. The circuit arrangement of Figure 7 is identical to that of Figure 2 and the only difference in the arrangement is that the layers of actuating material having electrodes 16', 17', 18' are of circular shape in the arrangement of Figure 7. From the description which has been given in connection with Figure 2 and in connection with Figure 1 of the above-mentioned

cording application, it will be seen that the arrangement of Figure 7 is such that in its operation one of the plates expands in all radial directions while the other plate contracts in all radial directions, and vice versa. Thus the arrangement of Figure 7 effectively provides an actuating element of the diaphragm type wherein, upon application of the polarizing potential 32, an alternating voltage at the input circuit of tube 30 is associated with cup shaped "bending" motions of the operating element.

Each of the embodiments of the invention, as will readily be understood by those skilled in the art, can be used either as a generator of alternating voltages in response to bending motions of the actuating element or can be used to provide mechanical vibratory motion in response to an alternating current input thereto.

While the invention has been described with a certain degree of particularity, it is to be understood that it has been by way of example and that changes can be made without departing from the spirit and scope of the invention.

I claim as my invention:

1. A bender-type electromechanical device comprising, an even number of superimposed layers of dielectric material comprising two groups of elements one group of which is to expand and the other group of which is to contract and vice versa to provide a bender-type of electromechanical transducer element, unidirectional electrical-polarizing means for each of said layers, and electrical terminal-circuit connections to each of said layers such that the charges associated with a theoretical application of voltage thereto are of the same sign in each of said layers of one of said two groups of elements as the charge in each such layer due to said polarizing means while the charges in each of said layers of the other of said two groups of elements due to said applied voltage are of opposite sign from the charge in each such layer due to said such polarizing means whereby said device can be used to convert bending movements of said such transducer element into electrical energy or vice versa.

2. A bender-type electromechanical device comprising, two layers of dielectric material effectively comprising two groups of elements one group of which is to expand while the other group is to contract and vice versa to provide a bender-type of electromechanical transducer element, unidirectional polarizing means for each of said layers, and electrical terminal-circuit connections to each of said layers such that the charge associated with a theoretical application of voltage thereto is of the same sign in one of said layers as the charge due to said polarizing means while the charge in the other of said layers due to said applied voltage is of opposite sign from the charge due to said polarizing means, whereby said device can be used to convert bending movements of said transducer element into electrical energy or vice versa.

3. A bender-type electromechanical device comprising an even number of relatively thin and elongated layers of dielectric material comprising two groups of elements one group of which is to expand while the other group is to contract and vice versa to provide a bender-type of electromechanical transducer element, unidirectional electrical-polarizing means for each of said layers, and electrical terminal circuit-connections to each of said layers such that the charges associated with a theoretical application of voltage thereto are of the same sign in each of said layers

of one of said two groups of elements as the charge in each such layer due to said polarizing means while the charges in each of said layers of the other of said two groups of elements due to said applied voltage are of opposite sign from the charge in each such layer due to said such polarizing means, whereby said device can be used to convert bending movements of said such transducer element into electrical energy or vice versa.

4. A bender-type electromechanical device comprising an even number of relatively thin circular disks of dielectric material comprising two groups of elements one group of which is to expand radially while the other group is to contract radially and vice versa to provide a bender-type of electromechanical transducer element, unidirectional electrical-polarizing means for each of said disks, and electrical terminal-circuit connections to each of said disks such that the charges associated with a theoretical application of voltage thereto are of the same sign in each of said disks of one of said two groups of elements as the charge in each such disk due to said polarizing means while the charges in each of said disks of the other of said two groups of elements due to said applied voltage are of opposite sign from the charge in each of said disks due to such polarizing means, whereby said device can be used to convert cup-like bending movements of said transducer element into electrical energy or vice versa.

5. A bender-type electromechanical device comprising, an even number of superimposed layers of dielectric material comprising two groups of elements one group of which is to expand while the other group is to contract and vice versa to provide a bender-type of electromechanical transducer element, unidirectional electrical-polarizing means for each of said layers, electrical terminal-circuit connections to each of said layers such that the charges associated with a theoretical application of voltage thereto are of the same sign in each of said layers of one of said two groups of said elements as the charge in each said layer due to said polarizing means while the charges in each of said layers in the other of said two groups of elements due to said applied voltage are of opposite sign from the charge in each such layer due to said polarizing means, means for mechanically vibrating said transducer element, and electrical output means coupled to said terminal circuit connections for deriving and utilizing a corresponding electrical output from said transducer element.

6. A bender-type electromechanical device comprising, an even number of superimposed layers of dielectric material comprising two groups of elements one group of which is to expand while the other group is to contract and vice versa to provide a bender-type of electromechanical transducer element, unidirectional electrical-polarizing means for each of said layers, electrical terminal-circuit connections to each of said layers such that the charges associated with a theoretical application of voltage thereto are of the same sign in each of said layers of one of said two groups of said elements as the charge in each said layer due to said polarizing means while the charges in each of said layers in the other of said two groups of elements due to said applied voltage are of opposite sign from the charge in each such layer due to said polarizing means, means for supplying alternating electrical energy to said electrical terminal-circuit connections, and means for deriving and utilizing a corre-

sponding mechanical vibration from said transducer element.
